UNITED STATES PATENT OFFICE.

EDWIN BALL STIMPSON. OF BROOKLYN, NEW YORK.

MACHINE FOR CREEASING LEATHER AND THE LIKE.

1,194,791.

Specification of Letters Patent. Patented Aug. 15, 1916.

Application filed May 11, 1912. Serial No. 696,629.

To all whom it may concern:

Be it known that I, EDWIN B. STIMPSON, a citizen of the United States, residing at Brooklyn, in the county of Kings and State 5 of New York, have invented certain new and useful Improvements in Machines for Creasing Leather and the like, of which the following is a specification.

My invention relates to an improvement 10 in machines for creasing leather and the like.

The object of the machine is to produce by 15 means of heated creasers permanent markings or creases in leather or other suitable material fed through the machine. Each creasing tool has a plurality of dies thereon 20 of different designs and is rotatable so as to present one or another of said dies at will to the work. The machine further produces any number of parallel creases simultaneously 25 at any desired distance apart. The creasers are also individually adjustable so as to give the desired depths of crease, either all of the same depth or of different depths.

The improved means by which I accomplish 30 the above results are shown in the accompanying drawings, although it will be understood that the machine of said drawings is only one of the specific embodiments

which my invention is adapted to take. In these drawings, Figure 1 is an end elevation of a machine within my invention; Fig. 2 is a front elevation of the upper part 35 of said machine; Fig. 3 is a detail view on an enlarged scale, said view being taken on the line 3—3 in Fig. 2 looking in the direction of the arrows, and showing parts broken away to receive internal structure; and Fig. 4 is a section on the line 4—4 in Fig. 3 looking in the direction of the arrows.

1 designates a suitable machine frame carrying a work-supporting table 2, a driven feed roll 3, and a driving pulley 4. It will be sufficient to state that the pulley 4 is rotatable on a shaft supported by the frame and may be clutched to the shaft at will by means of an ordinary clutch device 5 operated by a lever 6. On the pulley shaft is a pinion 7 (Fig. 1) which gears with a similar pinion 8 on the feed roll 3. With this mechanism, said feed roll 3 is driven at the desired speed. The upper surface of this roll is nearly on a level with the supporting table 2.

5 The ends of the machine frame have each a pair of horizontal flanges 1^a located one

over the other and having holes therein which are in vertical alinement to receive with sliding bearing fit a rod 12, one at each end of the machine. Adjustable collars 13 60 on these rods prevent them from dropping through these holes in the flanges by bearing against the upper side of the lower flanges. 14—14 are compression spiral springs on the rods between the upper 65 flanges and said collars serving to keep the rods normally depressed.

11 is the vertically movable head of the machine and is connected at its ends to the rods 12. This head supports the creasing 70 tools operatively over the feed roll 3.

The aforesaid springs 14 serve to depress the head 11 and its creasing tools against the work; vice versa, said parts are elevated by stepping on the foot lever or treadle 15. 75 This treadle is rigid at its rear end with a long rock shaft 16 having its bearings in the ends of the machine frame. This rock shaft has a pair of levers 17 projecting rigidly therefrom just outside of the respective ends 80 of the machine frame. The free ends of these levers are connected to points above them on the ends of the frame by tension springs 18. 20—20 (Figs. 1 and 2) are connecting rods which operatively connect 85 the levers 17 with the horizontally disposed levers 21, which latter tilt about the pins 22 on the ends of the frame. The forward ends of these levers are semi-circular and at their extremities have horizontally disposed round 90 studs or pins 23 which extend under the projecting ledges 24 constituting the ends of the creaser supporting head 11.

The result of the devices thus far described is that when the operator steps on 95 the treadle 15, he elevates simultaneously the curved or forward ends of the tilting levers 21, and consequently elevates simultaneously from both ends the head 11. This permits the operator to feed the leather under the 100 creasers. This having been done, he removes his foot from the treadle and the heavy springs 14 carry and hold the creasers down to their work. The tension springs 18 are relatively weak and merely serve to 105 hold the treadle 15 and the related parts in a normal position. The adjustable bolts 19 in the levers 17 prevent these springs 18 from lifting the treadle too high by striking against the bottom of the lower cross-pieces 110 of the ends of the machine frame. Each creasing device consists of a body portion 30

(Fig. 1) having a dove-tail slot in its top which receives endwise through it the dove-tailed lower edge 11^a of the machine head 11. It will be noted from Fig. 1 that the ends of the machine frame are open so that the creasing devices can be passed through said ends to insert or remove them from the dove-tail portion of the machine head.

Fig. 2 shows graduations on the front of the head 11 to permit the operator to adjust the positions of the creasing devices along the head accurately as desired. To lock the individual creasing devices in their adjusted positions against endwise displacement along the head 11, each has a handle 31 pivoted between a pair of lugs 60 (Figs. 2 and 3) extending from the body portion above the front incline of the dove-tail 11^a, the pivoted end of said handle having a cam surface 33 which binds against said incline when the handle is pressed down as in Fig. 3 but which does not bind against it when the handle is pressed up. The body portion 30 has a pair of spaced apart forwardly and downwardly extending legs 34 (Figs. 1 and 3) connected at their base by pivot pin 41 and at their ends by a pivot pin 35.

40 is a hook (Fig. 3) rigid with the rotatable pin 41 between these legs 34, and 42 is an operating handle at the right hand side of each creasing device in Fig. 2, (also compare Fig. 3) said handle being rigid with the end of this same pin 41.

36 is a U-shaped member for supporting the actual creasing tool. The front leg 36^a of this member is pivotally connected to the body portion 30 by the pin 35 on which it is supported between the legs 34.

38 is an adjustment screw supported at the upper end of the front leg 36^a to bear against the front of the body portion 30, and this screw has a lock nut 39 for use in maintaining the desired adjustment of the screw. The upper end of the rear leg 36^b of this U-shaped member is connected by the coiled tension spring 37 with a part of the body portion 30 below it. This tension spring has the effect (compare Fig. 3) of pivoting the U-shaped member about the pin 35 to force the creasing tool which it supports yieldingly against and into the work L. The actual creasing tool may take the form shown consisting of a disk 50 (Figs. 3 and 4) rotatably supported on a pin or axle 50^a between the bifurcated bottom portion 36^c of the U-shaped member. This disk has a plurality of creasing dies 51 around its periphery.

52 are ratchet teeth on the side of the disk and 53 is a spring pawl projecting from the U-shaped member into a position to engage said teeth. This pawl permits the disk to be rotated in anti-clockwise direction to bring any desired die 51 in operating position, but prevents said disk from being ro-

tated by the passage of the work L through the machine by the feed roll 3 (Fig. 3).

61 is a gas pipe leading from the main supply pipe 62 to deliver gas to a burner located adjacent each disk 50.

The previously described hook 40, by pressing down on the handle 42, is adapted to hook under a pin 43 which connects the sides of the bifurcated bottom portion 36^c of the U-shaped member. The result is that the entire U-shaped member and its creasing tool or disk are pivoted upwardly about the pin 35 into a non-operating position out of contact with the work, so that the disk 50 can be rotated as previously described or so that the entire creasing device can be slid endwise off the dove-tailed supporting edge 11^a of the machine head, or so that any of the creasing devices can be merely allowed to hang idly from said head. The tension of the spring 37 in each creasing device assists in giving the requisite creasing pressure to the die. On the other hand, the adjustment of the set screw 38 determines the depth to which the spring shall force the die into the surface of the work.

Of course, it will be understood that changes in construction may be made in the devices of the drawings without departing from the spirit and scope of the invention, and these are intended to be covered hereby.

What I claim is:

1. In a creasing machine, the combination with a frame having spaced ends, one of which has an open portion, of a head mounted in the frame and having a supporting portion for creasing devices, one end of which is exposed in the open portion of the end, a creasing device that is movable through the open portion of the end and is applicable to and removable from the supporting portion of the head through said open portion of the end, and means mounted on the end of the frame and engaging the head in the open portion of said end for moving said head.

2. In a creasing machine, the combination with a frame having spaced ends provided with openings, of a head mounted in the frame and having a depending portion for supporting creasing devices, the ends thereof being in line with the open portions of the frame, creasing devices movable through the open portions and applicable to and removable from said exposed ends through the same, means for yieldingly moving the head downwardly, and devices mounted on the ends of the frame and engaging the ends of the head in the openings of said frame and above the supporting portion for elevating the head.

3. A creasing machine having an open ended frame, a vertically movable head having a lower edge adapted to slidably support creasing devices, a creasing device having

its top constructed for interlocking engagement with said lower edge, said creasing device being adapted to be applied to or removed from said head through the opening 5 in the end of the frame, and means on said creasing device for locking it in different positions of adjustment along said edge.

4. A creasing machine having a vertically movable head; and a creasing device supported from said head, said device comprising a creasing tool which is a rotatable support having a plurality of creasing dies around its periphery.

5. A creasing machine having a vertically movable head; a creasing device supported from said head, said device comprising a creasing tool which is a rotatable support having a plurality of creasing dies around its periphery; and pawl and ratchet 20 means which permits the rotatable support to be rotated in one direction only.

6. In combination with the head of a creasing machine, a creasing device comprising a body part which removably engages 25 the machine head to support the creasing device therefrom, and further comprising a creasing tool part pivotally supported from said body part; means which yieldingly depresses said tool part; and a handle-actuated 30 pivoted hook on the body part adapted to engage the other part and support it in an elevated position.

7. In combination with the head of a creasing machine, a creasing device comprising a body part which removably engages 35 the machine head to support the creasing device therefrom, and further comprising a creasing tool part pivotally supported from the body part having an upright arm above said pivot adjacent the front of the body 40 part, and having a rearwardly extending horizontal arm on the other side of said pivot; a creasing tool supported on said rearward arm; means which yieldingly separate said rearward arm from said body part; 45 and an adjustment screw through the upper end of said upright arm bearing against the front of the body part.

8. A creasing machine having a vertically movable head with a lower edge having a 50 dove-tail cross section; a creasing device having a corresponding dove-tail slot in its top; and a locking handle pivoted to the top of the creasing device having a cam surface on its pivoted end adjacent the dove-tailed lower edge of the machine head to be brought into and out of locking engagement therewith.

In testimony whereof I affix my signature in presence of two witnesses.

EDWIN BALL STIMPSON.
